UNITED STATES PATENT OFFICE

2,065,177

GAS-PRODUCER MACHINE OR UNIT FOR
USE IN CONJUNCTION WITH METALLUR-
GICAL AND LIKE FURNACES

John Fallon, Birmingham, England

Application July 28, 1934, Serial No. 737,334
In Great Britain December 11, 1933

2 Claims. (Cl. 48—87)

This invention has reference to gas-producer machines or units for supplying heating gas to metallurgical and like industrial furnaces, and is an improvement in or development of the mechanical stoker type of apparatus wherein one side wall of the fuel bed is adapted to be oscillated to and from the opposite wall for crushing purposes, and which incorporates a feed screw, mechanism for actuating said oscillating side wall, and a reciprocating ash-clearing device beneath the fuel bed, all actuated from a common power-driven shaft, provision being also made for a primary air blast direct into the fuel bed.

The invention consists primarily in a gas-producer machine or unit, of the mechanical stoker type referred to, wherein the fuel feed device is adapted for indexed variable speed control, wherein the reciprocating ash-clearing device is actuated with an independently variable displacement from the fuel feed device, wherein the primary air blast from a blower is adapted for independent volumetric regulation and wherein a single master control lever is provided for the simultaneous operation of the respective controls of the fuel feed, the ash discharge and the air blast after their independent initial settings.

The invention further consists in a construction wherein said machine or unit is mounted on a base provided with wheels and wherein the whole of the driving and control mechanism, including the motor, the speed-reduction gear, the blower, and the fuel, ash, and air controls, is mounted on a front plate or frame forming a detachable element of the machine or unit.

In order that the invention may be clearly understood and readily carried into practice, reference may be had to the appended explanatory drawings, in which:—

Figure 1 is a front elevation of a gas-producer machine or unit embodying the invention.

Figure 2 is a side elevation of the same.

Figure 3 is a sectional side elevation of the same.

In this machine or unit the coal is fed from a supply hopper 1 to the fuel bed 2 by means of a spiral screw 3 driven by an intermittent ratchet gear 4 and 5 and link 6 from an electric motor 7 through a speed-reduction gear 8, this screw 3 being adapted for a variable feed governed by a master control lever 9 associated with the upper section of a calibrated dial 10 and geared through sector wheels 46 and 47 to a shield 48 adjustably interposed between the ratchet wheel 4 and pawl 5 and being arranged to deliver the coal over a spreader 11. The coal feed device is associated

with a fuel consumption meter 12 and is operatively linked at 13 to the pawl 14 of an intermittent ratchet wheel 49 for rotation of an intermediate shaft 15 which in turn is connected by worm 16 and worm wheel 17 to a counter-shaft 18 from which the reciprocating ash-clearing plough 19 is actuated through the medium of an eccentric 20, link 21, bell-crank levers 22, and connecting rods 23, the displacement of this ash-clearing plough being governed by a pointer 24 associated with a calibrated quadrant 25 so as to control the setting of a shield 50 adjustably interposed between the ratchet-wheel 49 and pawl 14. The oscillating side wall 26 of the fuel bed 2 is of sectional fire-bar construction, with a bottom extension 27 designed to crack and disintegrate any clinker or fused ash, and is actuated from the motor 7 by spur wheels 28, worm 29, worm wheel 30, eccentric shaft 31, and links 32. The master control lever 9 governing the coal feed of the screw 3 is arranged by means of a locking and control knob 34 in interlocking relation to a pointer 33 associated with the lower section of the calibrated dial 10, this pointer 33 being operatively connected by means of a cam 35, lever 52, link 53 and lever arm 54 to the flap 35 of an air valve 36 on the discharge side of a blower 37 also driven by the motor 7, the blower having a connection to the fuel bed 2 to provide the air supply, which is capable of volumetric regulation by the pointer 33, which can be set in any desired relation to the coal feed, and this differential control of the air valve 36 also enabling full air blast to be applied during the starting-up period, after which the valve is set and clamped by the knob 34 in correct relationship to the master control lever 9 for operating conditions. The machine or unit also incorporates a water jacket or vaporizer 39 which is fed from a supply cistern 40 and which not only maintains a predetermined temperature of the refractory lining 41 of the fuel bed, thereby preventing adhesion of clinker, but also provides steam for air blast saturation, which steam is delivered into the base of the fuel bed 2 by way of side pipes 42.

It will be seen that the ash extraction mechanism may be set by means of the index pointer 24 at any reasonable ratio to the coal feed, that is to say, so that the ash-clearing plough 19 may give a displacement of say 5, 10, 15, 20, 25, or 30 per cent according to the ash content of the fuel, and that on thus setting this indexed ash discharge in proportion to the coal feed, the discharge is maintained and varied in the 55

same ratio that the coal feed is varied according to the capacity required from the machine or unit, and as the air supply may also be set by means of the index pointer 33 and maintained in any desired relation to the coal feed, it will further be seen that, in effect, both the ash-clearing device and the air supply device are calibrated according to the percentage of ash and to the pressure of air required, and that 10 after these initial calibrations all the controls are operated in the predetermined ratios with one movement of the master control lever 9. Subject to the electric motor drive, therefore, the gas-producer machine or unit is completely 15 automatic in operation, both in regard to fuel feed, air supply, and ash discharge, being equally suitable for handling bitumen and anthracite coal or coke of the lowest and cheapest grades, entirely eliminating the human element, and 20 being fitted with indexed controls which ensure precision delivery of high quality gas at constant pressure and temperature for any industrial furnace application. In operation the machine or unit maintains a fuel bed of constant 25 depth and may be set to gasify fuel efficiently from one-tenth of its capacity up to full capacity, either intermittently or continuously, during full load or during stand-by periods, whether applied to heat treatment furnaces, 30 forge furnaces, welding or melting furnaces, kilns, or like metallurgical furnaces.

The whole of the driving and control mechanism, including the motor, the speed-reduction gear, the blower, and the fuel, ash, and air 35 controls, are mounted on a front plate or frame 43 forming a detachable element of the machine or unit. This front plate or frame with its supporting mechanism can be separately removed from the machine or unit, whilst the machine or unit as a whole, by reason of its supporting base 44 mounted on wheels 45, can readily be separated from the furnace with which it is operated. The machine or unit can 40 be applied to new furnaces or to existing furnaces of various types, without necessitating any alteration of the furnaces, and enabling the cheapest available grades of fuel to be utilized.

What I claim as my invention and desire to secure by Letters Patent is:

50 1. In a gas-producer machine of the mechanical stoker type for supplying heating gas

to metallurgical and like industrial furnaces, and which comprises a feed screw for delivery of fuel to the fuel chamber, a side wall which is adapted to be oscillated to and from an opposite side wall for crushing purposes, a mechanism for actuating said oscillating ash-clearing device beneath said fuel chamber, and a common power-driven shaft for actuating said elements, the combination of an indexed control mechanism for varying the feeding rotation of 10 said fuel feed screw, means for actuating said ash-clearing device through the medium of said fuel feed screw, an indexed control mechanism for independently varying the displacement of 15 said ash-clearing device, a blower for delivery 15 of an air blast to said fuel chamber, an indexed control mechanism for independently varying the volume of said air blast, and a master control lever for the simultaneous operation of the said various control mechanisms after the independent initial settings thereof.

2. In a gas-producer machine of the mechanical stoker type for supplying heating gas to metallurgical and like industrial furnaces and which comprises a feed screw for delivery of 25 fuel to the fuel chamber, a side wall of which is adapted to be oscillated to and from an opposite side wall for crushing purposes, a mechanism for actuating said oscillating side wall, a reciprocating ash-clearing device beneath said fuel chamber, and a common power-driven shaft for actuating said elements, the combination of 30 an indexed control mechanism for varying the feeding rotation of said fuel feed screw, means for actuating said ash-clearing device through the medium of said fuel feed screw, an indexed control mechanism for independently varying the displacement of 35 said ash-clearing device, a blower for delivery of an air blast to said fuel chamber, an indexed control mechanism for independently varying the volume of said air blast, a master control lever for the simultaneous operation of the said various control mechanisms after the independent initial settings thereof, an electric motor, a speed-reduction gear, and 40 a detachable front frame plate constituting a mounting for the whole of the driving and control mechanism, including said motor, speed-reduction gear, blower and said control mechanisms.

JOHN FALLOON.
